of furniture, especially of adjustable chairs, and to provide an adjustable reclining chair, the movable parts of which may be easily brought into various positions while the user of the chair rests thereon.

UNITED STATES PATENT OFFICE

Patent No. 2,266,055. Filed Jan. 10, 1939. Patented Dec. 16, 1941.

ADJUSTABLE RECLINING CHAIR

Hans Luckhardt, Berlin-Dahlem, and Anton Lorenz, Berlin-Schöneberg, Germany

Application January 10, 1939, Serial No. 256,114
In Germany January 12, 1938

7 Claims. (Cl. 155—106)

Our invention relates to an adjustable reclining chair, and more particularly to an adjustable reclining chair, in which a back-rest, a seat, a leg-rest and connecting link-means are pivotally interconnected with each other to form a polygonal structure with unequal sides, and wherein one point of the polygonal structure is pivoted to a support and cooperating sliding means are arranged on the support and on one member of the polygonal structure to control the movement of the members of the polygonal structure.

One object of our invention is to simplify the construction of reclining chairs of the above described type.

Another object of our invention is to provide a reclining chair, the movable parts of which may be easily brought into various positions while the user of the chair rests thereon.

Still another object of our invention is to provide a reclining chair of the above described type, in which the load is transferred to the support at the lowest possible point of the support.

In order to carry out our invention into practice, we provide an adjustable reclining chair comprising a support, a back-rest, a seat, a leg-rest, said seat extending between a lower point of said back-rest and an upper point of said leg-rest and being pivoted thereto, said back-rest having at least one lower extension extending downwardly beyond the pivot point between the back-rest and the seat, at least one connecting link, said connecting link extending between a lower point of said extension and an intermediate point of said leg-rest and being pivoted thereto, said seat, the upper portion of the leg-rest between said upper point and said intermediate point, said connecting link and said extension forming a polygonal structure, having unequal sides, one point of said polygonal structure being pivoted to said support, and cooperating cam means and sliding means arranged on the support and on the connecting link.

The above mentioned objects and advantages as well as other objects and advantages will be more fully disclosed in the following specification reference being had to the accompanying drawings forming part of this specification in which:

Fig. 1 is a left side end view of an adjustable reclining chair, the left hand side frame being omitted.

Fig. 2 is partly a front elevational view and partly a sectional view of the adjustable reclining chair, taken on line 2—2 of Fig. 1, the left hand side frame being omitted.

Fig. 3 is a left side end view of another embodiment of an adjustable reclining chair, the left hand side frame being omitted.

Fig. 4 is partly a front elevational view and partly a sectional view of the adjustable reclining chair shown in Fig. 3, taken on line 4—4 of Fig. 3.

Fig. 5 is a side elevational view of still another embodiment of an adjustable reclining chair.

Fig. 6 is a front elevational view of the reclining chair shown in Fig. 5, the leg-rest being partly broken away, and

Fig. 7 is a fragmentary perspective view of the reclining chair shown in Fig. 5.

Referring now to Figs. 1 and 2, 10 indicates a back-rest, 12 indicates a seat, and 14 indicates a leg-rest of an adjustable reclining chair, which has the form of a club chair. The seat 12 extends between the back-rest 10 and the leg-rest 14. The front end of the seat 12 is pivoted to the upper end of the leg-rest at 16, the rear end of the seat 12 is pivoted to the back-rest 10 at 18. The back-rest 10 has two extensions 20, one on each side of the chair, which extend downwardly beyond the pivot point 18 between the back-rest 10 and the seat 12. Said extensions 20 are integral with the back-rest. On each side of the chair, the rear end of a connecting link 22 is hinged to one of the extensions 20 at 24, and the front end of each link 22 is pivotally connected with an intermediate point of the leg-rest 14 at 25. The extension 20 of the back-rest 10, the seat 12, the upper portion of the leg-rest 14 and the connecting link 22 form a polygonal structure having unequal sides, the shortest side being the upper portion of the leg-rest between the pivots 16 and 25.

The chair has two side frames 26, which are connected with each other by means of two transverse members 28 and 30. The structure 26, 28, 30 forms the support of the chair. The side frames 26 may be covered with a layer 32 of a suitable covering material, such as fabric, leather or the like. The upper edges of the side frames 26 form the arm-rests of the chair.

One point of the polygonal structure 12, 14, 22, 20 is pivoted to the support 26, 28, 30. In the embodiments shown in Figs. 1 and 2, this point is coaxial with the pivot point 18 between the back-rest 10 and the seat 12. The bolt 18 is screwed into the side frame 26 and passes through holes in the back-rest and seat, so that the latter may rotate about the bolt 18.

In order to obtain various positions of the members of the polygonal structure swingably mounted at 18, the movement of the members of

said polygonal structure must be controlled. For this purpose, we provide cooperating sliding means on the support and on the connecting link. Each side frame 26 of the chair shown in Figs. 1 and 2 has a curved slot 34, and each connecting link 22 has a lug 36 provided with a hole. A cross-bar 38 passing through said holes is connected with the links 22, and the ends of said cross-bar 38 are in slidable engagement with said slots 34. If the user of the chair moves the back-rest 10 to the left (as seen in Fig. 1), the polygonal structure swings about the pivot 18 and the link 22 causes a sliding movement of the cross-bar 38 along the curved cam-like surface of the slot 34, so that the link 22 and the parts connected therewith are guided by the cross-bar 38 during the adjustment of the various positions of the polygonal structure. Thus, the leg-rest 14 is lifted and rotated about the pivot 25 and at the same time the front end of the seat 12 is lifted when the back-rest 10 is swung about the pivot 18 and is lowered. The sitting position of the polygonal structure is shown in full lines, the extreme reclining position is shown in dash lines. If the movable parts of the chair are in sitting position, the cross-bar 38 abuts against the lower end of the slot 34, and if the movable parts of the chair are in the extreme reclining position, the cross-bar 38 abuts against the upper end of the slot 34, so that the latter forms the stops for the extreme positions of the polygonal structure.

As will be apparent from the above description and drawings, the arrangement of the cooperating cam means and sliding means on the support and the link 22 being below the seat 12 permits the application of the load to the support at the lowest possible point. The slots 34 are covered by the covering layer 32 on the outside of the side frames, so that the construction of the cam means and sliding means is invisible and the reclining chair has the appearance of a usual club chair.

Figs. 3 and 4 illustrate another embodiment of our reclining chair. Similarly to the embodiment shown in Figs. 1 and 2, the support comprises the elements 26, 28 and 30, and the polygonal structure comprises the elements 12, 14, 22 and 20 and is pivoted to the support at 18. The cooperating cam means and sliding means, however, are of somewhat different form. The links 22 have a recess 40 forming a sliding cam surface, which rests on a cross-rod 42 the ends of which being secured to the side frames 26. If the back-rest 10 is lowered, the surface of the recess 40 slides on the cross rod 42 serving to guide the link 22 for upward swinging movement. The upper end of the recess 40 forms a stop for the sitting position of the polygonal structure, and the lower end of the recess 40 forms a stop for the extreme reclining position, when it abuts against the cross-rod 42.

Figs. 5 to 7 illustrate a further embodiment of the reclining chair, in which the support 260 is formed of tubular material. The polygonal structure comprises the lower extensions 200 of the back-rest 10, the seat 12, the upper portion of the leg-rest 14, and a single connecting link 22 in the middle of the chair. The two extensions 200 are bent inwardly as shown in Figs. 6 and 7. One end of each extension 200 is rigidly connected to the back-rest 10 by rivets 44 or the like, the other end of each extension 200 is hingedly connected to the rear end of the single connecting link 22 by means of a pivot 240. Ob-

viously, the extension 200 rigidly connected to the back-rest 10 is an equivalent of the extension 20 being integral with the back-rest 10 shown in Figs. 1 to 4. While the chair shown in Figs. 5 to 7 has only a single connecting link 22 pivotally connected to the middle of the leg-rest 14, the chair could be provided with two connecting links 22, one on each side of the chair as shown in the embodiment of the chair illustrated in Fig. 3. In such a case, the extensions 200 could be of straight form. The cam-like recess 40 of the link 22 shown in Figs. 5 to 7 is in slidable engagement with the cross-rod 42 secured to the bars 46 forming a part of the support.

Furthermore, Figs. 5 to 7 show, that the pivot 18 between the back-rest 10 and the seat 12 is not necessarily used for the pivotal connection between the polygonal structure and the support. According to Figs. 5 to 7, the polygonal structure is pivoted to the support by means of separate pivots 180 secured to the seat 12 on each side of the chair. Said pivots are rotatably mounted in lugs 48 secured to rods 50 forming a part of the support.

While we have shown only certain embodiments of a reclining chair, we do not wish that the invention be limited to said embodiments only. For example, the cam-like surface of the recess 40 or the slot 34 may have any other shape as may be required by the proportions of the elements of the polygonal structure. Furthermore, the recess 40 may be replaced by a cam attached to the link 22. Moreover, each link 22 may be provided with separate and independent rollers instead of a single cross-bar 38 connected to both lines, and said rollers or said cross-bar may be in slidable engagement with a curved or straight bar instead of a slot 34. Furthermore, the extension 20 shown in Figs. 1 to 4 may be replaced by a separate element rigidly secured to the back-rest, or a single connecting link 22 may be used instead of two links, one on each side of the chair. While according to Figs. 5 to 7 the seat is pivoted to the support, the back-rest could be pivoted to the support instead at a point spaced from the pivot point 18 connecting the seat with the back-rest. In the embodiments shown in the drawings, the extension 20 and the extension 200 are substantially in alignment with the back-rest. If desired, however, the extension 20 and the extension 200 could be arranged at an angle to the back-rest. Furthermore, separate stops could be arranged in the chair for limiting the end positions of the polygonal structure. Moreover, the chairs may be equipped with a locking device, by means of which the user of the chair may lock the movable parts of the chair in any desired position.

We have described preferred embodiments of our invention, but it is clear that numerous changes and omissions may be made without departing from the spirit of our invention.

What we claim is:

1. An adjustable reclining chair comprising: a support; a back-rest; a seat; a leg-rest; said seat extending between a lower point of said back-rest and an upper point of said leg-rest and being pivoted thereto; said back-rest having at least one lower extension extending downwardly beyond the pivot point between the back-rest and the seat; at least one connecting link; said connecting link extending between a lower point of said extension and an intermediate point of said leg-rest and being pivoted thereto; said seat, the upper portion of the leg-rest between

said upper and said intermediate point, said connecting link and said extension forming a polygonal structure having unequal sides; one point of said polygonal structure being pivoted to said support; and cooperating cam means and sliding means arranged on the support and on the connecting link.

2. An adjustable reclining chair as claimed in claim 1, in which said extension is an integral part of the back-rest.

3. An adjustable reclining chair comprising: a support; a back-rest; a seat; a leg-rest; said seat extending between a lower point of said back-rest and an upper point of said leg-rest and being pivoted thereto; said back-rest having at least one lower extension extending downwardly beyond the pivot point between the back-rest and the seat; at least one connecting link; said connecting link extending between a lower point of said extension and an intermediate point of said leg-rest and being pivoted thereto; said seat, the upper portion of the leg-rest between said upper and said intermediate point, said connecting link and said extension forming a polygonal structure having unequal sides; one point of said polygonal structure being pivoted to said support; and a sliding means associated with said connecting link; said support being provided with a cam-like surface, and said sliding means being in cooperative engagement with said cam-like surface.

4. An adjustable reclining chair as claimed in claim 3, said support having two side frames, one side frame on each side of the polygonal structure, two connecting links one at each side of the chair, and sliding means associated with each of said connecting links, each of said side frames being provided with a slot, and said sliding means being in cooperative engagement with said slots.

5. An adjustable reclining chair as claimed in claim 3, said support having two side frames, one side frame on each side of the polygonal structure, two connecting links one at each side of the chair, and a cross-bar associated with said connecting links, each of said side frames

being provided with a slot, and said cross-bar being in slidable engagement with said slots.

6. An adjustable reclining chair comprising: a support; a back-rest; a seat; a leg-rest; said seat extending between a lower point of said back-rest and an upper point of said leg-rest and being pivoted thereto; said back-rest having at least one lower extension extending downwardly beyond the pivot point between the back-rest and the seat; at least one connecting link; said connecting link extending between a lower point of said extension and an intermediate point of said leg-rest and being pivoted thereto; said seat, the upper portion of the leg-rest between said upper and said intermediate point, said connecting link and said extension forming a polygonal structure having unequal sides; one point of said polygonal structure spaced from the pivot point between the back-rest and the seat being pivoted to said support; and cooperating cam means and sliding means arranged on the support and on the connecting link.

7. An adjustable reclining chair comprising: a support; a back-rest; a seat; a leg-rest; said seat extending between a lower point of said back-rest and an upper point of said leg-rest and being pivoted thereto; said back-rest having at least one lower extension extending downwardly beyond the pivot point between the back-rest and the seat; at least one connecting link; said connecting link extending between a lower point of said extension and an intermediate point of said leg-rest and being pivoted thereto; said seat, the upper portion of the leg-rest between said upper and said intermediate point, said connecting link and said extension forming a polygonal structure having unequal sides; one point of said polygonal structure being pivoted to said support; a sliding cam surface on said connecting link; and means for guiding the connecting link for upward swinging movement as the back-rest is lowered, said means being mounted on said support and being in cooperative engagement with said sliding cam surface on the connecting link.

HANS LUCKHARDT.

ANTON LORENZ.
